STORED PRESSURE MEDIUM CONTAINER

Daniel Mapes, Upper Montclair, N. J., assignor
to Walter Kidde & Company, Inc., New York,
N. Y., a corporation of New York

Application April 9, 1932, Serial No. 604,336

1 Claim. (Cl. 220—63)

The present invention relates to fire extinguishing apparatus employing a fire extinguishing liquid propelled by a medium stored under pressure in a cartridge or other container and embodies more specifically an improved design of cartridge having the requisite strength to resist the pressure in the cartridge and having additionally corrosion resisting properties for enabling the strength of the cartridge and other desirable conditions to be maintained over a long period of time.

It has been customary to employ one of the various steels for pressure cartridges of the type in question but the resultant corrosion due to submersion or partial submersion of the cartridge in the liquid fire extinguishing medium has not only jeopardized the strength of the cartridge but has rendered illegible inscriptions which it is customary to make on the cartridge. Of course, there is the additional disadvantage of contamination of the liquid medium and formation of sediment with possibility of clogging the discharge line of the apparatus.

It would seem at first possible to overcome this defect by making the cartridge of a material highly resistant to corrosion but such materials are either costly or lacking in the requisite strength and in some instances porous to the passage of mediums stored under high pressure, such, for example, as liquid carbon dioxide.

The present invention therefore contemplates the provision of a container proper of relatively high tensile strength and non-porous material, but having relatively poor corrosion resisting properties, such, for example, as steel, and an envelope for the container completely surrounding it externally and of a material having relatively good corrosion resisting properties.

Such an envelope might consist of a shell of copper, lead or the like formed over the container proper, or the container proper might be coated with some corrosion resisting substance such as porcelain or rubber solution.

The invention also contemplates the provision of means for retaining the pressure medium within the cartridge and effecting its release therefrom, said means being formed of a material resistant to corrosion or of a material suitably guarded against corrosion, as by nickel-plating, at points where danger of corrosion exists.

The invention will now be described in greater detail in connection with the accompanying drawings, wherein:

Figure 1 is a view in vertical, central section

of a pressure cartridge or container in accordance with the invention.

Figure 2 is a central longitudinal sectional view of an extinguisher of the type with which the invention may be advantageously employed.

In Figure 2 of the drawings there is represented at 1 a standard shell or container for holding a liquid fire extinguishing medium, such as water, calcium chloride solution or other suitable fire extinguishing medium, which is filled into 10 the container up to the level of the filling indicator 2. The shell is provided with a handle 3 for carrying the extinguisher in an erect position, another handle 4 for carrying the extinguisher in an inverted position, a strainer 5, an outlet elbow 15 6 and a standard hose 7 coupled to the outlet elbow and having a discharge nozzle 8. A cage comprising an upper flange 9, a bottom plate 10 and suspension rods 11 is supported upon a shoulder 12 in the neck of the shell and in turn supports a cartridge 13 containing a medium under pressure, such as liquid carbon dioxide, for propelling the liquid fire extinguishing medium from the shell. The cartridge 13 is provided with a coupling 14 containing means for effecting release of the pressure medium from the cartridge, said releasing means becoming operative upon inversion and jarring of the shell, whereby to cause forcible engagement of the releasing means with a projection 15 formed on a cap 16 and extending within the shell. The cap 16 is threaded to the neck of the shell with an intervening gasket 17 which not only effects a leakage-tight joint with the shell but secures the flange 9 of the cage against movement. The cap 16 is otherwise standard, being provided with a rim 18 for carrying the extinguisher in an upright position and for effecting rotation of the cap.

With extinguishers of the type described it has been customary to make the pressure cartridge 40 13 of steel, which, because of its high tensile strength and imperviousness, is adapted to withstand the high pressure of the contained medium and to prevent leakage thereof from the cartridge. These cartridges, however, are subject 45 to considerable corrosion by reason of their submersion or partial submersion in various types of liquid fire extinguishing mediums, and this corrosion is not only undesirable by reason of its 50 weakening effect on the strength of the cartridge, but is likewise annoying because it renders illegible serial numbers, tare weights and other inscriptions usually made on cartridges of this type. Other attendant disadvantages will be readily

apparent and need not be further discussed herein.

It is therefore an object of the present invention to provide a pressure medium cartridge which not only has the desired strength and corrosion resisting properties but which is likewise economical to manufacture.

For this purpose, and with reference to Figure 1, the reference numeral 50 indicates a pressure medium cartridge or container made of relatively high tensile strength and non-porous material but having relatively poor corrosion resisting properties, such, for example, as steel. At 51 is shown an envelope for the container 50 completely surrounding it externally and of a material having relatively good corrosion resisting properties. Such an envelope might consist of a shell of copper, lead or the like formed into a cylinder with one end closed, as at 52, the container 50 being inserted in the shell and the shell being spun in to conform at 53 and 54 with the shoulder portion and the end portion respectively of the container 50. The invention also contemplates making the coupling 14 and the pressure medium releasing device contained therein from a material resistant to corrosion, so that, when the coupling is threaded into the neck of the container 50, as at 55, the container is completely protected against external corrosion by the shell 51 and the coupling 14. Alternatively, the invention contemplates making the coupling 14 of any suitable material and protecting all external portions thereof subject to corrosive action with a material resistant to corrosion, nickel-plating having been found to be very effective for this purpose.

While Figure 1 has been described with particular reference to a shell 51 of material resistant to corrosion, it will be apparent that Figure 1 may also represent the use of an envelope of porcelain or rubber solution or any other suitable corrosion resisting material applied to the con-

tainer 50 externally thereof in any suitable manner.

The invention also contemplates the use of additional corrosion preventing means at the junction 56, whenever it is deemed advisable to 5 adopt such additional protective measure.

From the foregoing description it will be seen that I have made decided improvements in stored pressure cartridges and containers for use with pressure propelled liquid fire extinguishing mediums, these improvements having been made with the economical factor as well as the operating and maintenance factors in mind. However, while the invention has been described with specific reference to the accompanying drawings, it 15 is not to be limited, save as defined in the appended claim.

I claim:

As an article of manufacture a vessel for retaining under pressure a fluid medium having fire 20 extinguishing properties and having a high pressure three-dimensional phase at ordinary temperatures, comprising a unitary structure consisting of a container proper of relatively high tensile strength and non-porous metal but having 25 relatively poor corrosion resisting properties, said container being formed with at least one end open, a closure member for an open end of the container having means to retain the fluid medium within the container proper, said closure 30 member having relatively good corrosion resisting properties at least at points in contact with media external thereto, and a shell of metal having relatively good corrosion resisting properties, but of lesser tensile strength than the metal of 35 the container proper, adapted to receive the container proper and to completely enclose it externally to a point adjacent said closure member and sealed at the closure member so as to permanently close off contact of the container proper 40 with media external thereto.

DANIEL MAPES.
